UNITED STATES PATENT OFFICE

GEORGE J. RUSSELL, OF WALTHAM, MASSACHUSETTS

LUBRICATING SYSTEM

Application filed March 18, 1930. Serial No. 438,736.

This invention relates to lubricating systems for use with apparatus having power cylinders operated by a non-compressible fluid such as oil, and also to means for removing air from such cylinders.

As air pockets are frequently formed in hydraulically operated cylinders while the latter are not operating, it is customary when such cylinders are operated after an idle period to blow out the air on the first stroke of the piston or to provide for performing this function automatically. Moreover, apparatus of this character usually includes many parts which require lubricant in different quantities and/or under different pressures. Heretofore the removal of air from the cylinders and the lubrication of the various parts have been treated as functions to be performed independently.

Objects of this invention are to utilize the pressure in a hydraulic power cylinder for supplying lubricant to various parts of a machine; to provide for removing air from a hydraulic cylinder through a lubricating system, and for delivering pressure fluid from the cylinder to the lubricating system; and also to provide apparatus of this character having an improved construction and arrangement of parts.

The single figure in the drawing is a longitudinal section taken through main and auxiliary power cylinders of a broaching machine.

For the purposes of illustration the features of this invention are shown as applied to an hydraulically operated broaching machine of the type disclosed in my copending applications Serial No. 433,490 and Serial No. 433,491, both filed March 5, 1930, to which reference may be had for a more general statement of the purposes and mode of operation of such a machine. The portion of the broaching machine shown in the drawing is representative of a large class of machines, operated by hydraulic power, to which this invention may be applied. This machine comprises a bed plate 10 which carries the heads 11 and 12 for a main power cylinder 13. These heads are provided with ports 14 and 16 for admitting and discharging an operat-

ing fluid, preferably a lubricating oil, to operate the piston 17 which is disposed within the cylinder. The piston rod 18 extends through suitable packing 19 in the head 11 for transmitting power to the broaching apparatus (not shown) during the working or broaching stroke and also for returning a stock carrier (not shown) after the working stroke has been completed.

An auxiliary cylinder 21 is fitted with a piston 22 and is provided with ports 23 and 24 for admitting pressure fluid to reciprocate the piston. This piston carries a rod 26 which extends through a suitable packing 27 in the end of the cylinder and is connected to a member 28 for operating an auxiliary of the machine, as for operating a pilot (not shown) in a broaching machine of the type disclosed in my aforesaid applications.

Capillary tubes 31 are connected to the ends of the main cylinder 13 and through a connection 32 to a closed pressure tank 33. In a like manner capillary tubes 34 are connected to the ends of the auxiliary cylinder 21 and through a connection 36 to the closed pressure tank 33. A connection 37 extends between the upper side of the closed tank 33 and an open tank 38, this connection being normally closed by a pressure relief valve 39 which is interposed therein and is set to open at a predetermined pressure to permit flow from the tank 33 to the open tank 38.

A plurality of tubes 41 are connected, preferably to the under side of the closed tank 33, for supplying lubricant such as oil from this tank to various parts requiring lubrication. It will be understood that each of the tubes may extend to one or more parts requiring lubrication, as is the usual practice in systems of this kind. Each of the tubes 41 is provided with a sight gauge 42 and a manually controlled valve 43 for regulating the flow through these connections. The tank 33 is also equipped with a gauge 44 to indicate the level of liquid in the tank. The overflow tank 38 may also be employed for maintaining the desired head of fluid on a reversible flow pump (not shown) which supplies pressure fluid for operating the main and the auxiliary cylinders.

After one of the cylinders, as the main cylinder 13, has remained idle for a period of time, it is quite probable that air pockets may be formed within the cylinder, or the pressure fluid delivered to the cylinder to operate the piston may contain air which should be removed to assure efficient operation of the apparatus. During the working stroke of the piston 17 such air contained in the operating fluid will be forced through the capillary tubes 31 as the piston approaches the end of the cylinder, and on repeated operation of the piston the air passing into the capillary tubes will eventually be ejected through the tube 32 into the closed tank 33 from whence it may escape through the relief valve 39 into the open tank 38. The tubes 31 or at least the cylinder ends of these tubes have a very small inside diameter and therefore offer a large resistance to passage of the operating fluid; hence these tubes tend to remain filled with this fluid while the piston is not operating. Moreover, during operation of the piston, operating fluid will be continually forced through these tubes into the closed tank 33, thereby building up a pressure in this tank. This pressure is augmented by fluid supplied in a like manner through the connection 36 from the auxiliary cylinder 21, and it will also be clear that air will be displaced from the auxiliary cylinder through the capillary tubes 34 and the connection 36 to the pressure tank 33 in the same manner as described with reference to the main cylinder. In this way any desired pressure can be built up in the closed tank 33, and this pressure may then be utilized for forcing oil through the tubes 41 to various parts requiring lubrication, the flow to each of the parts being controlled by the regulating valves 43. Should the pressure at any time become excessive in the tank 33, the relief valve 39 will open and relieve this pressure to the open tank 38. In the event that a greater pressure is desired in the closed tank 33 than can be developed by delivering fluid through the capillary tube 31, it will be seen that this pressure can be provided by increasing the number of such tubes without increasing their sectional flow area. When used with lubricating oil suitable for machines of this character, the tubes 31 and 34 should have an internal diameter of approximately .0010 to .0015 of an inch.

I claim:

1. The combination with a fluid motor of the kind utilizing a relatively non-compressible working fluid and comprising a cylinder and a piston therein, of a pressure tank for supplying lubricant to a lubricating system and a tube extending between the cylinder and the tank for conducting fluid from the cylinder to the pressure tank, at least a portion of the tube being capillary to the working fluid, whereby the tube may be effective for sealing the cylinder to prevent air from

passing from the tank to the cylinder during non-working periods and to provide for removal of air from the cylinder during working strokes of the piston.

2. The combination with a fluid motor of the kind utilizing a relatively non-compressible working fluid and comprising a cylinder and a piston therein, of a pressure tank for supplying lubricant to a lubricating system and connections from the ends of the cylinder to the pressure tank for conducting fluid from the cylinder to the pressure tank, each of these connections having at least a portion thereof capillary to the working fluid, whereby the connections may be effective for sealing the cylinder to prevent air from passing from the tank to the cylinder during non-working periods and to provide for removal of air from the cylinder during working strokes of the piston.

3. The combination with a fluid motor of the kind utilizing a relatively non-compressible working fluid and comprising a cylinder and a piston therein, of a pressure tank, means providing passages for conducting working fluid from the cylinder to the pressure tank during operation of the piston, each of these passages having a portion thereof capillary to the working fluid to provide for sealing the passages during non-working periods and also to provide for removal of working fluid and gas during working strokes of the piston, a number of tubes for conducting fluid from the pressure tank to parts to be lubricated, and means for controlling the flow through the tubes.

4. The combination with a fluid motor of the kind utilizing a relatively non-compressible working fluid and comprising a cylinder and a piston therein, of a pressure tank, means providing passages for conducting working fluid from the cylinder to the pressure tank during operation of the piston, each of these passages having a portion thereof capillary to the working fluid to provide for sealing the passages during non-working periods and also to provide for removal of working fluid and gas during working strokes of the piston, means providing a plurality of passages for conducting fluid from the pressure tank to parts to be lubricated, an open tank, a connection between the pressure tank and the open tank, and a relief valve in said connection for relieving excessive pressure in the pressure tank.

5. In an apparatus comprising main and auxiliary power cylinders of the kind using a relatively non-compressible fluid, and a piston in each cylinder, the combination of a closed pressure tank, connections between the ends of each cylinder and said tank, each connection having a portion thereof capillary to the working fluid to provide for sealing the passages during non-working periods and also to provide for removal of working fluid

and gas during operating strokes of the piston, an open tank, means for relieving pressure from the closed pressure tank to the open tank, connections for supplying lubricant from the closed pressure tank to parts to be lubricated, and means for controlling the flow through said connections.

Signed by me at Torrington, Connecticut,
this 14th day of March, 1930.
